UNITED STATES PATENT OFFICE

WILLIAM C. LOYD, OF GARY, INDIANA, AND HOWARD G. MCILVRIED, OF MCCANDLESS TOWNSHIP, ALLEGHENY COUNTY, PENNSYLVANIA, ASSIGNORS TO AMERICAN SHEET AND TIN PLATE COMPANY, OF PITTSBURGH, PENNSYLVANIA, A CORPORATION OF NEW JERSEY

ROLLING-MILL GUIDE

Application filed April 6, 1928. Serial No. 267,996.

This invention relates to rolling mill guides, and more particularly to entering guides for strip mills and has for its object the provision of an entering guide which is divided longitudinally, and the parts of which may be simultaneously adjusted toward or away from each other to accommodate varying widths of strips or sheets.

Heretofore, guides of this class have generally been constructed so that each part separately been constructed so that each part separated from the other and such parts were separately adjustable.

In the drawings

Figure 1 is a sectional elevation showing a guide constructed in accordance with this invention applied to a roll housing.

Figure 2 is a sectional plan thereof.

Figure 3 is an entering side elevation.

Figure 4 is a fragmentary sectional elevation showing the manner in which the guide is supported on the rest-bar and the manner in which the nuts are mounted in the guide.

Referring more particularly to the drawings, the letter A designates a standard rolling mill housing of the four-high type of mill, which consists of a pair of small working rolls 2 and materially larger backing-up rolls 4.

A rest-bar member B is secured between the sides of the mill housing at the entering side of the mill. The rest-bar B has guide-flanges 5 and 6 along its respective longitudinal edges which are provided with longitudinally extending undercut grooves 7 and 8, respectively, to receive locking bolts.

A box-type entering guide C, which is split longitudinally to form right and left-hand parts 9 and 10, is supported on the guide-flanges 5 and 6 of the rest-bar B. The guide-parts 9 and 10 are each provided with guide-flanges 12 which extend inwardly and are slidably engaged on the guide-flanges 5 and 6 of the guide-bar. Locking bolts 14 are mounted in the guide-parts 9 and 10 and have their heads engaged in the undercut grooves 7 and 8 and are adapted to lock the guide-parts in adjusted position on the rest-bar.

A shaft 16 is journaled in bearings 17 on the rest-bar B and extends longitudinally of said bar. The ends of the shaft 16 are provided

with right and left-hand threads, respectively, and nuts 18 are mounted against rotation in the guide-parts 9 and 10 and are in threaded engagement with the opposite ends of said shaft.

A worm-wheel 20 is secured on the shaft 16 and is in mesh with a worm 21 secured on a shaft 22 journaled in bearings 23 on the bar B and extending at right angles to the shaft 16.

The rest-bar B is provided with a housing portion 24 which encloses the worm 21 and worm-wheel 20 so that they may be suitably lubricated.

A bearing bracket 25 is secured on the rest-bar B and is provided with a bearing 26 for the outer end of the shaft 22 and with bearings 27 at each end in which a shaft 28 is journaled.

The shaft 28 is provided with a bevel gear 29 which is meshed with a bevel gear 30 on the shaft 22 and a hand-wheel 31 is secured on the end of the shaft 28 by which the shaft may be rotated.

In operation, when it is desired to adjust the entering guide-parts 9 and 10, it is only necessary to loosen the locking bolts 14 and then to operate the hand wheel 31, which will rotate the shaft 28, and the shaft 28 will rotate the shaft 22 through the gears 29 and 30. The shaft 22 will, in turn, rotate the threaded shaft 16 by means of the worm 21 and worm-wheel 20, and the shaft 16 will be threaded into or out of the nuts 18 carried by the guide-parts 9 and 10 and will thus cause a simultaneous movement of the guide-parts along the rest-bar. After the guide-parts have thus been simultaneously adjusted they will be again locked in position by tightening the bolts 14.

By providing the novel adjusting arrangement of this invention the labor of adjusting the guides is materially reduced, the time necessary to adjust the guides is reduced to a minimum, the guides are always centered, and more accurate adjustments are possible.

While we have shown and described one specific embodiment of our invention it will be understood that we do not wish to be limited thereto, since various modifications

may be made without departing from the scope thereof as defined in the appended claims.

We claim:-

1. The combination with a strip mill comprising a roll housing having working rolls journaled therein, of an entering guide mechanism, said entering guide mechanism comprising a rest-bar secured between the sides 10 of the roll housings on the entering side thereof, a box-type entering guide projecting forwardly into proximity to said rolls, said guide being composed of right and left-hand parts and being slidably mounted on 15 said rest-bar, a shaft journaled in bearings on said rest-bar and extending transversely of said guide, right and left-hand threads on said bar, nuts mounted in each of said entering guide-parts and having threaded engagement 20 with said shaft, and means for rotating said shaft to cause said nuts to move said guide-parts simultaneously toward and away from each other, said means including a worm-wheel on said shaft, a worm in mesh 25 with said worm-wheel, a shaft and suitable gearing for operating said worm, and a housing formed integral with said rest-bar and enclosing said worm and worm-wheel.
2. The combination with a strip mill comprising a roll housing having working rolls journaled therein, of an entering guide mechanism, said entering guide mechanism comprising a rest-bar secured between the sides 30 of the roll housing on the entering side thereof, a box-type entering guide projecting forwardly into proximity to said rolls, said guide being composed of right and left-hand parts and being slidably mounted on said rest-bar, a shaft journaled in bearings on said rest-bar, 35 and extending transversely of said guide, right and left-hand threads on said bar, nuts mounted in each of said guide-parts and having threaded engagement with said shaft, means for rotating said shaft to cause said 40 nuts to simultaneously move said entering guide-parts toward and away from each other, said means comprising a worm-wheel on said shaft, a second shaft journaled in bearings on said rest-bar and extending at right angles 45 to said first named shaft, a worm on said second named shaft and meshed with said worm-wheel, a third shaft extending transversely of said housing and journaled in bearing brackets carried by said rest-bar, 50 gearing connecting said second and third named shafts, and a hand-wheel on said third shaft whereby said shafts may be rotated to adjust said guide-parts.

In testimony whereof, we have hereunto
set our hands.

WILLIAM C. LOYD.
HOWARD G. McILVRIED.
